UNITED STATES PATENT OFFICE.

WALTER W. STRYKER, DECEASED, LATE OF DAYTON, OHIO, BY EDWARD T. JONES,
ADMINISTRATOR, OF DAYTON, OHIO.

RAILROAD SPIKE.

1,425,715.

Specification of Letters Patent. Patented Aug. 15, 1922.

Application filed April 18, 1922. Serial No. 555,349.

To all whom it may concern:

Be it known that WALTER W. STRYKER, deceased, citizen of the United States, a former resident of Dayton, in the county of 5 Montgomery and State of Ohio, did invent certain new and useful Improvements in Railroad Spikes, of which the following is a specification.

This invention relates to railroad spikes 10 and the object is to produce a spike which will retain itself securely in place, and which as it is driven into place will cause a shoulder on the spike to be forced into locked engagement with the underside of the track rail- 15 supporting plate by the resilient action of the railroad tie, the latter effecting a turning movement of the spike about its longitudinal axis until the shoulder is forced under the rail plate.

20 The invention consists in the construction, combination and arrangement herein fully described, illustrated and claimed.

In the accompanying drawings:

Fig. 1 shows in perspective the improved 25 railroad spike and the relation thereof to a railway rail, tie and rail plate;

Fig. 2 is a vertical section through the tie and rail plate, with the spike in elevation;

Fig. 3 is a side view of the spike;

30 Fig. 4 is a cross section through the spike inverted looking upwardly toward the head of the spike;

Fig. 5 is a side view of the spike slightly modified; and

35 Fig. 6 is a cross section through the same.

In the drawings there are shown fragments of a railway tie 10, a rail supporting plate 11, and a railway rail 12. The plate 11 is formed with the usual non-circular 40 (usually square or rectangular) holes 13 for the rail fastening spikes.

The improved spike comprises a shank 14, and a head 15 to hold down the base flange of the rail 12 as shown in Fig. 1. The 45 shank has a pointed end 16 and has, in the preferred embodiment of the invention, opposite flat sides or surfaces 17. It is preferred to make the shank rectangular or with all four sides flat. The head 15 also has opposite flat side edges 18 to be used in extracting the spike as will appear.

On one, two or more sides of the shank 50 there are formed cam faced projections 19 terminating in shoulders 20, the cam surfaces 21 leading up to said shoulders, the lat-

ter being substantially triangular in plan, as shown.

The shoulders 20 are situated so as to engage the under side or surface of the rail plate 11 when the spike is driven to its final 60 place, as shown in Figs. 1 and 2. The cam faces 21 are parallel to each other (see Fig. 4) so that as the spike is driven into place the spike is partially turned about its longitudinal axis by reason of its passing 65 through the rectangular hole 13 in the rail plate 11, the cam faces 21 riding against the walls of the plate 11 on opposite sides of the hole 13.

As soon as the shoulders 20 pass under 70 the rail plate, the cam faces 21 are pressed in the opposite direction by the fibers of the wooden tie 10 due to the inherent resiliency of the latter. The spike is thereby turned about its longitudinal axis and the shoulders 75 20 are forced under and into engagement with the under side of the rail plate 11.

Any force tending to lift the spike out of the tie will be transmitted by the shoulders 20 to the rail plate, but as the rail plate is 80 held down by the load on the rail and also by other spikes, it is clear that no local force is tending to pull the spike out of the tie. Any force tending to loosen the spike is distributed by means of the rail plate to the 85 other spike or spikes. If the force tending to loosen the spike is produced by pressure of the load tending to turn or roll the track rail over, then the shoulders 20 will prevent the spike from coming out of the rail plate 90 even though the tie fails to hold the spike as in the case where the wood of the tie rots around the spike.

The cost of manufacturing the improved 95 spike should not exceed the cost of the standard spike, it being only necessary to alter the spike-forming die.

What is claimed is:

1. A railroad spike having opposite flat sides and formed on such sides with projecting cam lugs situated in position to engage against the under side of the rail supporting plate when the spike is in its final position, the cam faces of said lugs being adapted to cause a turning movement of the 105 spike on its longitudinal axis as it is driven into place.

2. A railroad spike having a flat side surface, a projecting shoulder adapted to engage the bottom surface of a track rail-sup- 110

- porting plate, and a cam surface terminating at said shoulder and acting as the spike is driven into place to cause a turning movement of the spike about its longitudinal axis 5 until said shoulder reaches the underside of said plate and is forced under the rail plate, by the resilient action of the tie.
3. In combination with a railway tie and rail-supporting plate having a non-circular 10 spike hole, a rail spike having a flat side surface, a projecting shoulder, and a cam sur-

face leading to said shoulder and acting as the spike is driven into place to cause a turning movement of the spike about its longitudinal axis until said shoulder reaches the 15 underside of said plate and is forced into engagement with the under side of the rail plate by the resilient action of the tie.

In testimony whereof I affix my signature.
EDWARD T. JONES,
Administrator of the estate of Walter W. Stryker, deceased.
